US0D1078099S

(12) **United States Design Patent** (10) **Patent No.:** **US D1,078,099 S**
(45) **Date of Patent:** **** Jun. 3, 2025**

(54) **COMBINED DOORS WITH ROOM**

(71) Applicant: **Apple Inc.**, Cupertino, CA (US)
(72) Inventors: **Jonathan P. Siegel**, San Francisco, CA (US); **Christopher M. Green**, Woodside, CA (US); **James Andrus**, San Francisco, CA (US); **David del Villar Fernandez**, San Francisco, CA (US); **David Nelson**, London (GB); **Stefan Behling**, London (GB); **David Summerfield**, London (GB); **James McGrath**, Cupertino, CA (US); **Ed Wright**, San Jose, CA (US); **Bo Yoon**, San Francisco, CA (US); **Ton Men Banh**, Santa Clara, CA (US)

(73) Assignee: **Apple Inc.**, Cupertino, CA (US)

(**) Term: **15 Years**

(21) Appl. No.: **29/772,026**

(22) Filed: **Feb. 26, 2021**

Related U.S. Application Data

(63) Continuation of application No. 29/584,026, filed on Nov. 10, 2016, now Pat. No. Des. 912,274, which is

(57) **CLAIM**

The ornamental design for combined doors with room as shown and described.

DESCRIPTION

FIG. 1 is a front perspective view of combined doors with room in a first state showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the combined doors with room of FIG. 1 in a second state;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The dashed broken lines in the figures show portions of the combined doors with room that form no part of the claimed design.

1 Claim, 10 Drawing Sheets

Related U.S. Application Data

a continuation of application No. 29/517,044, filed on Feb. 9, 2015, now Pat. No. Des. 771,836.
